UNITED STATES PATENT OFFICE.

WILLIAM H. RAMSDELL, OF NEW YORK, N. Y.; GEORGE H. BRUCE ADMINISTRATOR OF SAID
WILLIAM H. RAMSDELL, DECEASED.

METALLIC WASHTUB-COVER.

No. 885,707.

Specification of Letters Patent. Patented April 21, 1908.

Application filed June 24, 1905. Serial No. 266,827.

To all whom it may concern:

Be it known that I, WILLIAM H. RAMSDELL, a citizen of the United States, residing at New York, in the county of New York and State of New York, have invented new and useful Improvements in a Metallic Washtub-Cover, of which the following is a specification.

This invention relates to metallic wash tub covers.

The objects of the invention are to improve and simplify the construction of such devices; furthermore, to increase their strength and to decrease the expense attending their manufacture.

With the foregoing and other objects in view, which will appear as the description proceeds, the invention resides in the combination and arrangement of parts and in the details of construction hereinafter described and claimed as a practical embodiment thereof.

In the accompanying drawing forming part of this specification;—Figure 1 is an under plan view of a wash tub cover constructed in accordance with the invention. Fig. 2 is a top plan view thereof. Fig. 3 is a section on the line 3—3 of Fig. 1. Fig. 4 is a section on the line 4—4 of Fig. 2. Figs. 5 and 6 are views similar to Figs. 1 and 2 respectively of a modified construction. Fig. 7 is a section on line 7—7, Fig. 5, and Fig. 8 is a section on line 8—8, Fig. 6.

Like reference numerals indicate corresponding parts in the different figures of the drawing.

As shown in the drawing, the improved cover comprises a body portion 1 having the central portion thereof stamped down as indicated at 2 in order to take up any slack in the metal and to render the cover as rigid as possible. The front and rear edges of the cover 1 are bent to form casings 3, 4 in which are placed filling pieces 5 of wood or other suitable material. The filling piece 5 at the rear edge of the cover is adapted to receive the screws 6 which are used for holding the hinges 7 in position. The side edges of the cover 1 are bent to form casings 8 which render the cover strong and rigid. The casings

3 and 4 at the front and rear of the cover are formed with wings 9 which overlap the side casings 8 as shown clearly in Fig. 1, and are soldered securely to said side casings. The overlapping seam which is thus formed at each corner of the cover renders the same much more strong and rigid than would be possible if straight seams were employed. The forward casing 3 preferably is provided with rubber buffers or cushions 10, for the usual purpose.

The modified construction illustrated by Figs. 5 to 8 inclusive is practically the same as that shown in Figs. 1 to 4, except that the side casings 8 are dispensed with, and the side edges of the cover 1 are bent inwardly upon themselves to form flat strengthening members 11 composed of two thicknesses of metal as shown. The modified construction further differs from the construction illustrated in Figs. 1 to 4, in that only the rear casing 4 is provided with a filling piece 5, the front casing 3 being empty as shown, in order to decrease the weight of the cover and the expense attending its manufacture. The filling piece 5 is employed, as previously described to receive the screws 6 of the hinges 7.

The improved cover of this invention is strong, simple, durable and inexpensive in construction.

Having thus described the invention what is claimed as new is;—

A rectangular metallic wash tub cover comprising the body thereof having a central depression the surrounding marginal edge of the cover being bent angularly to provide rectangular casings which serve to reinforce the same, the front and rear casings serving to receive a filling of fibrous material, and said front and rear casings having reinforcing strips on their under surfaces, and cushions secured to the opposite ends of the front reinforcing strip, substantially as specified.

In testimony whereof, I affix my signature in presence of two witnesses.

WILLIAM H. RAMSDELL.
